UNITED STATES PATENT OFFICE.

WILLIAM MILLS, OF BIRMINGHAM, ENGLAND.

GRENADE.

1,232,590.

Specification of Letters Patent. Patented July 10, 1917.

Application filed June 15, 1915. Serial No. 34,233.

To all whom it may concern:

Be it known that I, WILLIAM MILLS, a subject of the Kingdom of Great Britain, residing at Atlas Aluminium Works, Grove 5 Street, Birmingham, in the county of Warwick, England, engineer, have invented certain new and useful Improvements in Grenades, of which the following is a specification.

10 This invention comprises certain improvements in or relating to grenades, land mines, and the like.

The type of grenade to which the present invention relates comprises or involves a 15 hollow body adapted to contain the explosive charge, and within or in connection with which a cap or primary ignition device is incorporated adapted to be fired by a suitable striker, and in relation to which cap or primary 20 ignition device a time fuse is incorporated, means being provided for the reception of the fuse or of the part thereof in the vicinity of the cap in order to retain the fuse or this part thereof in its proper 25 position.

According to the present invention, the means for receiving and retaining in position the time fuse, or the part thereof in the vicinity of the cap or primary ignition device, are of a character whereby the fuse, or 30 the portion thereof which is to be disposed adjacent to the cap or primary ignition device, may be assembled in a line or direction axially of the cap or primary ignition device, or at right angles to the plane of the 35 cap.

The fuse may at a point near to its extremity in the vicinity of the cap or primary ignition device be bent or diverted laterally, 40 and the means for receiving and retaining in position the fuse, may accommodate and retain in position the portion of the fuse at the bend, and also a lateral portion of the fuse beyond the bend, and the fuse may 45 then be bent or diverted through a second angle so that the remaining part of the fuse is parallel with the part of the fuse in the vicinity of the cap. In such an arrangement the lateral part of the fuse thus bent is 50 thereby received and retained in position by the means provided for this purpose, and the fuse can nevertheless be assembled in a direction axially of, or at right angles to, the plane of the cap or primary ignition 55 device.

Conveniently for the purpose of my inven-

tion I employ a cap holder which is separable from and adapted to be inserted within the end of a tubular portion in which the striker is adapted to operate. This cap holder is perforated axially from end to end, and within the perforation at the inner extremity, the cap is suitably inserted. The fuse, after being bent to the desired form, can then be readily inserted into the desired position in relation to the cap by a purely axial movement. At the face of the cap holder remote from that at which the cap occurs, there is advantageously on one or both sides of the perforation a transverse groove in which the laterally bent part of the fuse is adapted to be disposed, this bent part of the fuse being thereby supported on both sides by the portions of the cap holder occurring one on each side of the groove. The cap holder may be rotatably mounted within the tubular part in which the striker operates, and around the groove part of the cap holder there may be an annular recess in which, if desired, the fuse may be disposed and arranged to extend around any suitable part of the circumference to thereby provide for a variable increase in the length of the fuse and consequent increase of the time involved between the firing of the cap and explosion of the charge. A closure member suitably assembled in relation to the body of the grenade may be at its inner surface adapted to form a stop co-operating with the grooved face of the cap holder, so that the latter is thereby retained in position and such closure member is thereby enabled to also retain the fuse in its appropriate position.

In order that this invention may be clearly understood and readily carried into practice, reference may be had to the appended explanatory three sheets of drawings, upon which:—

Figure 1 is a sectional elevation of one suitable form of hand grenade according to the present invention.

Fig. 2 is an inverted plan of the grenade shown in Fig. 1, with closure member removed.

Fig. 3 is an inverted perspective view of an enlarged scale of the cap holder shown in Figs 1 and 2.

Fig. 4 illustrates separately the cap, cap holder, fuse, and detonator in the form in which they may be collectively introduced into, or removed from, the grenade.

Fig. 5 is a sectional elevation of the cap holder shown in Fig. 3, illustrating a modified method of securing the cap therein.

Fig. 6 shows a cap holder and part by 5 which it is carried, and illustrates the method of accommodating varying lengths of time fuses.

Fig. 7 is a part-sectional elevation of a cap holder, illustrating a further modified 10 method of securing the cap therein.

Fig. 8 is a sectional elevation of a further modification of the present invention.

Fig. 9 illustrates in sectional elevation a 15 still further modified embodiment of the present invention.

In a convenient embodiment of the present invention, as shown in the drawings, *a*, is the body of the grenade, within the interior of which a housing *b* is suitably incorporated, within which housing *b* a spring-impelled striker *c* is adapted to operate. The cap which this striker *c* is adapted to fire is carried by a plug *d* which fits within the one extremity of the central tubular 25 housing *b*, said plug *d* being rotatable in relation to the housing, and having, beyond the end of the housing, a U-shaped portion, or two arms, *e*, *e* with an intermediate groove or lateral opening, in the center of 30 which groove is the aperture or perforation *f* leading to the cap *g*. The one end of the time fuse *h* can be passed into this central perforation, and the fuse can pass laterally between the arms in either direction toward 35 the aperture or entrance to the detonator housing *i*. The detonator housing *i* may be integral with the central housing *b*, and at the end of the two housings there is a cup formation, within the plane of the edge of 40 which the connecting part of the fuse is adapted to lie. The outer surfaces of the arms *e*, *e*, of the cap plug *d* may be curved to form, with the outer wall of the cup, an annular or substantially annular groove or recess, in the base of which there is a perforation or opening *j* leading to the detonator 45 *k*. The fuse passing out of the perforation *j* may, instead of passing directly into the groove or opening in the cap plug, be continued around this annular recess for any desired part of the circumference, and may then turn in toward the perforation *f* leading to the cap *g*, the cap plug being rotated to an appropriate position to provide for this, as 55 shown at Fig. 6. Different lengths of time fuses may thus be accommodated to suit the requirements of different periods of time which may be required to elapse between the operation of the striker and the explosion of the grenade. By reason of the cap plug *d* being detachable and replaceable without any screwing operation, the fuse *h* can be assembled in relation to the detonator *k* and cap plug *d* containing the cap 60 before either of the latter members have 65

been assembled, after which the cap plug, detonator, and fuse can be collectively placed in position without any difficulty or danger. The cap plug is furnished with a shoulder *l* or shoulders, which limit the extent to which it can be inserted in the central housing.

After the parts have been assembled, as last described, the closure member *m* is assembled. This closure member may be in 70 the form of a plug adapted to be screwed into the aperture in which the cup portion of the internal member involving the housings *b*, *i*, is screwed, the same screw-thread being employed for the cup formation and 75 for the plug, the cup formation being screwed inwardly beyond the external surface of the body. Alternatively, the cup member, when screwed into place, may have its externally screw-threaded surface projecting outwardly beyond the external surface of the body, and a cap may then be screwed upon the projecting portion of the cup member so that such cap is screwed upon the same external screw thread as that by which 80 the cup portion is screwed into the spherical body of the grenade. In a still further alternative arrangement, the closure member 85 *m* may be assembled by a bayonet joint or other suitable means of connection. The closure member *m* is adapted to engage with the outer face of the cap plug and to retain the latter in position with its shoulder *l* against the face of the part in which 90 it is inserted.

If desired, I may provide between the closure members *m* and the fuse, a washer or protecting member, this washer or protecting member may be retained from rotation, as for instance, by providing it with a projection adapted to coöperate with a notch provided in the body of the grenade, and in such washer, in screwing up the closure member *m*, a purely axial pressure is applied to the fuse, and cap plug, and the latter are relieved from the torsional stress which they would otherwise experience by reason of their frictional contact with the inner surface of the closure member while the latter is being screwed up. The cap 100 plug *d* being rigidly retained in position by the closure member *m* constitutes an anvil upon or in relation to which the cap is struck and fired by the hammer. If desired, the portions *e* of the cap plug may 105 be dispensed with, and the separable cap plug instead of being retained in position by the closure member *m*, may be rigidly retained in position by other means, as, for instance, by a screw or screws engaging 110 with the cap plug and also with the part by which such plug is carried. Figs. 8 and 9 hereinafter more particularly referred to illustrate other methods of incorporating 115 the anvil.

In order to satisfactorily secure the cap within the cap plug *d*, and to prevent its being pushed out of the latter in the operation of inserting the fuse, the cap may, as shown in Figs. 1, 2 and 4, be furnished with arms or extensions *n*, *n*, projecting through the perforation *f* in the plug, which projections *n*, *n* may be bent outwardly at right angles to lie within the groove between the two arms *e*, *e*, of the cap plug. Or an equivalent result may be obtained by heading or expanding the edge of the tubular portion of the cap over the parts of the cap plug at the bottom of the transverse groove therein, as shown at Fig. 5. Or at its inner extremity the cap plug may be furnished around its circumference, or at intervals around its circumference, with an annular ridge or flange *w*, Fig. 7, or with tongues, ribs, or projections, which, after the cap has been inserted, may be contracted around or forced inwardly upon the head of the cap, to thereby retain the latter in its perforation, the head being adapted to rest upon the inner surface of the cap plug. If desired, both of these methods of retaining the cap in the plug may be adopted in connection with the one cap.

The present invention permits of the cap, cap holder, fuse, and detonator combined as shown in Fig. 4 being introduced into, and removed from, a grenade in order to provide safety in carriage, and thus the operations of assembling the various parts can be carried out easily and safely.

For the purpose of releasing the sliding or longitudinally-moving hammer or striking member *c*, which is incorporated within the internal housing *b*, and which hammer is controlled by a suitable spring *o*, the hammer or striker may be furnished with a head or annular flange *h* adapted to project out of the body of the grenade, such head or flange may be adapted to be engaged by the forked extremity of a lever *q* which lies upon the surface of the body *a* of the grenade and extends a distance around the latter. Such lever is adapted to be disposed between two elongated projections or flanges *r*, *r* upon the outer surface of the body, and at a point near to the head of the striker such flanges are furnished with slots or grooves adapted to form bearings for trunnions or projections *t* provided one on each side of the lever *q*. When the ends *s* of the tail of the lever *q* is retained against the outer surface of the body *a*, the forked extremity on the other side of the trunnions engages with the head or flange *h* of the striker *c*, and retains it in its retracted condition. A pin *u* may be passed through the flanges between which the lever *q* lies, such pin occupying a position above or outside of the lever to retain the latter in this position. When it is desired to use the grenade, the

tail of the lever is retained against the body *a* by hand, or by the throwing appliance, the pin *u* is removed, the grenade is thrown, and upon the grenade being released by the hand or throwing appliance, the lever *q* by a pivotal movement, releases the striker, which latter fires the cap.

The lever may, if desired, be, as shown in Figs. 8 and 9, applied to a handle with which the grenade is furnished. In Fig. 8, the tubular housing *y* for containing the spring-impelled striker *c* is contained within the handle. The anvil *x* which corresponds with the cap plug *d*, in Fig. 1, is separable and removable, but is rigidly retained from axial displacement between the housing *y* for the striker, and the detonator housing *z*, being disposed in a hollow extension of the handle in the arrangement shown in Fig. 8, and within the enlarged extension of the detonator housing in the arrangement shown in Fig. 9. The housing *y* for the striker constitutes or is provided with the handle, and such housing of the striker may be screwed into an enlarged extension of the housing *z* for the detonator, which enlarged extension is in turn screwed into the hollow body of the grenade.

Any suitable means may be adopted in the arrangement shown in Figs. 8 and 9 for retaining the time fuse in appropriate relationship to the cap, so that it shall not be blown out upon the firing of the latter. For this purpose the time fuse may be sheltered within or in relation to the cap or anvil *x*, or internal points or projections may be provided upon the cap or anvil adapted to engage with the external surface of the time fuse, and so retain the latter from axial movement. As in the case previously described, the cap *d*, anvil *x*, fuse *e*, and detonator *g* can be collectively inserted or removed when the handle is detached.

In connection with the present invention I may employ the invention comprised in my prior patent, No. 1,178,092, but I do not in this application make any claim to anything claimed in my said concurrent application.

What I claim as my invention and desire to secure by Letters Patent is:

1. In a grenade in combination, a spring impelled striker, an external member controlling said striker and adapted to be released by the hand or throwing appliance in the act of throwing the grenade, said striker being adapted to explode a percussion cap for setting off a time fuse, an anvil for said percussion cap adapted to be assembled in the grenade by a sliding motion only, and means for clamping said anvil against a normally fixed portion of the grenade.

2. In a grenade in combination, a spring impelled striker, an external member controlling said striker and adapted to be re-

leased by the hand or throwing appliance in the act of throwing the grenade, said striker being adapted to explode a percussion cap for setting off a time fuse, an anvil for said percussion cap adapted to be assembled in the grenade by a sliding motion only, said anvil surrounding said cap and a portion of the cap being extended outwardly in relation to the main portion thereof and serving 5 to prevent the extraction of the cap from the anvil, and a member for retaining said anvil in the grenade.

3. A grenade or the like comprising in combination a body *a*, a spring impelled 10 striker *c*, an externally pivoted lever *g* controlling said striker and adapted to be released by the hand or throwing appliance in the act of throwing, a chamber for said striker, an anvil in the striker chamber ar- 15 ranged to co-operate with said striker in exploding a cap, said anvil being adapted to accommodate a time fuse and being adapted to be inserted into said chamber by a sliding motion only, a percussion cap carried by 20 said anvil and retained from axial movement in either direction in relation thereto, and a member having screw threaded relation with a part of the grenade other than the anvil and adapted to hold the anvil in 25 place.

4. The combination of an anvil adapted to be assembled in an explosive device having a spring impelled striker, a percussion cap assembled and retained in said anvil, said 30 anvil and cap having communicating openings adapted to receive the end of a time fuse of the cord type, said anvil being adapted to be assembled in the explosive device by a sliding motion only and having a projection 35 thereon for limiting the extent of insertion of the anvil into the explosive device, and means for clamping said anvil against a fixed portion of the grenade.

5. The combination of an anvil adapted 40 to be assembled in an explosive device having a spring impelled striker, a percussion cap assembled and retained in said anvil, said anvil and cap having communicating openings adapted to receive the end of a 45 time fuse, a fuse of the cord type having the end thereof inserted in and retained in said anvil, a detonator attached to the other end 50 of said fuse, said anvil, fuse and detonator

forming a unit, and means for clamping said anvil against a fixed portion of the grenade. 55

6. The combination of a grenade having a spring impelled striker, of an anvil adapted to be inserted in said grenade by a sliding motion only, a percussion cap assem- 60 bled and retained in said anvil, said anvil and cap having communicating openings for receiving the end of a time fuse of the cord type, a detonator assembled and retained on the other end of said fuse, said anvil, cap, fuse, and detonator forming a unit and said 65 grenade having seats for said anvil and said detonator so arranged that the anvil, deto- nator, and fuse can be inserted in the gre- 70 nade as a unit, and means for clamping said anvil against a fixed portion of the grenade. 70

7. The combination of a grenade having a spring impelled striker, of an anvil adapted to be inserted in said grenade by a sliding motion only, a percussion cap assem- 75 bled and retained in said anvil, said anvil and cap having communicating openings for receiving the end of a time fuse of the cord type, a detonator assembled and retained on the other end of said fuse, said anvil, cap, 80 fuse and detonator forming a unit and said 85 grenade having seats for said anvil and said detonator so arranged that the anvil, deto- nator, and fuse can be inserted in the gre- 90 nade as a unit, and means for clamping said anvil against a fixed portion of the grenade. 90

8. In a grenade in combination, a spring impelled striker, an external member con- 95 trolling said striker and adapted to be re- leased by the hand or throwing appliance in the actual throwing of the grenade, said 90 striker being adapted to explode a percu- sion cap for setting off the time fuse, an 95 anvil for said percussion cap adapted to be assembled in the grenade by a sliding motion only, and means for clamping said anvil against a fixed portion of the grenade, said anvil having a groove on the face toward 100 said clamping means for the reception of part of said fuse.

In witness whereof I have hereunto set my hand in the presence of two witnesses.

WILLIAM MILLS.
